UNITED STATES PATENT OFFICE.

HENRY E. BRUNNER, OF HAYWARD, CALIFORNIA.

PLASTERER'S HAWK.

1,001,811.

Specification of Letters Patent. Patented Aug. 29, 1911.

Application filed March 13, 1911. Serial No. 614,281.

To all whom it may concern:

Be it known that I, HENRY E. BRUNNER, a citizen of the United States, residing at Hayward, in the county of Alameda and 5 State of California, have invented a new and useful Plasterer's Hawk, of which the following is a specification.

The object of my invention is to provide an implement which is lighter in weight 10 than are any of the plasterers' hawks heretofore invented or marketed, yet one that is practical, strong and rigid.

My hawk is made throughout of thin sheet metal of peculiar conformation and 15 disposition necessary to the attainment of my object and purpose.

I will here note how I differ from and improve upon the metal hawks heretofore invented. In metallic plasterers' hawks heretofore invented the face plate is formed of a plate of metal requiring considerable thickness and consequent weight of metal to insure the maintenance of a plane surface and 20 a true alinement of the edges on each side. I 25 obviate undesirable or unnecessary weight by using light thin sheet metal and compensate for the flexibility of the metal by means of reinforcing angles and braces as herein-after shown and described. Plasterers' 30 hawks heretofore invented have had handles made detachable by means of notches and lips or by threaded screw devices. The handle of my hawk is permanently attached to the face plate, but being cylindrical in 35 form may, by leaving the end open, be used as a socket for the insertion of a removable handle if desired by the user.

The accompanying drawings illustrate my invention and in them similar letters refer 40 to similar parts in the several views.

Figure 1 is a sectional view with thickness of the metal exaggerated for better illustration. Fig. 2 is a plan view from the lower or handle side.

In the drawings A is a rectangular face 45 plate with reinforcing angles B turned on the edges thereof.

C is a rectangular reinforcing plate with stiffening angles D, turned on the edges thereof and having a circular recessed aperture I in the center, into which is secured the end of the handle H by means of the annular flange J projecting therefrom as shown. The rivets E secure the reinforcing plate C to face plate A and are countersunk to leave the surface of said face plate 50 plane and flush. Brace plate F is in form a very shallow pyramid with a flattened apex having on its outer edges reinforcing angles G projecting under and secured by 55 angles B on face plate A, and in its center having a circular aperture K to fit around and secure handle H as shown. Handle H is cylindrical in form and is preferably closed on the by plate L though said handle 60 may be used with the end open for insertion of a removable handle of wood or other material.

I claim:

In a sheet metal plasterer's hawk the combination of a face plate having down turned edges, a reinforcing plate having down turned edges and a recessed central aperture, said reinforcing plate being secured to said face plate by means of rivets flush on 70 the plane of said face plate, a brace plate in form of a pyramid with a flattened apex 75 with an aperture in its center and upturned outer edges, said edges engaging and locking under downturned edges of the 80 face plate, a cylindrical handle projecting through the aperture in the brace plate and the end thereof secured into the aperture in the center of the reinforcing plate.

HENRY E. BRUNNER.
